(73) Assignee: **Kubota Corporation**, Osaka (JP)

(57) **CLAIM**

The ornamental design for an armrest for construction equipment, as shown and described.

(**) Term: **14 Years**

DESCRIPTION

(21) Appl. No.: **29/474,463**

FIG. 1 is a perspective view of the armrest for construction equipment according to the invention;

(22) Filed: **Sep. 26, 2014**

FIG. 2 is a front elevation view of the armrest for construction equipment of FIG. 1;

(51) **LOC (10) Cl.** **15-03**

FIG. 3 is a rear elevation view of the armrest for construction equipment of FIG. 1;

(52) **U.S. Cl.**

FIG. 4 is a right side elevation view of the armrest for construction equipment of FIG. 1;

USPC **D15/28**

FIG. 5 is a left side elevation view of the armrest for construction equipment of FIG. 1;

(58) **Field of Classification Search**

FIG. 6 is a top plan view of the armrest for construction equipment of FIG. 1;

USPC .... D15/10, 17, 22-26, 28, 30; D12/192; D21/329; D34/28, 35; 74/491, 469, 74/471 R, 471 XY; 280/752; 296/1.09, 191, 296/153; 297/411.36, 217.3, 411.2, 411.21; 180/333, 315, 326, 332, 329, 331, 90, 180/334

FIG. 7 is a bottom plan view of the armrest for construction equipment of FIG. 1;

See application file for complete search history.

FIG. 8 is a second perspective view of the armrest for construction equipment of FIG. 1, showing the armrest in its construction equipment environment;

(56) **References Cited**

FIG. 9 is a third perspective view of the armrest for construction equipment of FIG. 1, showing the armrest in its construction equipment environment; and,

U.S. PATENT DOCUMENTS

FIG. 10 is a fourth perspective view of the armrest for construction equipment of FIG. 1, showing the armrest in its construction equipment environment.
